WILLIAM H. CURTIS, OF DENVER, COLORADO.

WAGON FOR CIRCUS-TENTS.

1,184,672.

Specification of Letters Patent. Patented May 23, 1916.

Application filed August 25, 1913. Serial No. 786,357.

To all whom it may concern:

Be it known that I, WILLIAM H. CURTIS, a citizen of the United States, residing in the city and county of Denver and State of Colorado, have invented new and useful Improvements in Wagons for Circus-Tents; and I do declare the following to be a full, clear, and exact description of my invention, such as will enable others skilled in the art to which it appertains to make and use the same, reference being had to the accompanying drawings, and to the figures of reference marked thereon, which form a part of this specification.

My invention relates to improvements in wagons for circus canvas and its object is to provide a wagon by virtue of which the canvas used in circuses may be conveniently and quickly loaded and unloaded from the wagon.

Another object of the invention is to provide a wagon which obviates the necessity of folding and dragging the canvas upon the ground to be loaded or unloaded from the wagon, thus greatly prolonging the life of the canvas.

Another object of the invention is to provide a simple and efficient wagon which facilitates the packing and unpacking of the canvas.

Another object of the invention is to provide a wagon of the class specified, the mechanism of which is so arranged as to cause any water which may be in the canvas to be pressed out of the same when the latter is packed upon the wagon, thus greatly lessening the weight of the canvas for purposes of transportation.

Another object of the invention is to provide a wagon of the class specified provided with certain mechanism by virtue of which the canvas is caused to be packed firmly and compactly on the wagon.

Still another object of my invention is to provide an extremely simple and efficient wagon of the class set forth which obviates the necessity of manually folding and porting the canvas to the ordinary conveyance.

Still another object of my invention is to provide a wagon upon which the canvas may be packed and kept in a packed condition without being removed from the wagon.

With these and other objects in view I will proceed to describe my invention with reference to the accompanying drawing forming a part hereof.

In these drawings Figure 1 is a side elevation of my improved wagon for circus canvas; Fig. 2 is a cross sectional view of the same; Fig. 3 is a rear end view of the same; Fig. 4 is a section through the bearing or journal of the spool carried by the running gear of the wagon.

Corresponding and like parts are referred to in the following detail description and indicated in all the views of the accompanying drawings by the same reference characters.

Let the numerals 5 and 6 designate respectively front and rear wheels of the wagon, respectively mounted upon axles 7 and 8. The numeral 9 designates the body or frame work of the wagon, fixedly connected with the rear axle 7 and connected with the front axle 8 by means of a swivel or turn table 10. This frame or body 9 is composed of the usual front and rear bolsters 12 and 13, the two bolsters being connected by means of longitudinal beams 14 and 15. The mechanism described in the foregoing is substantially the same construction employed in the ordinary make of wagons and is described here only for the purpose of illustrating my invention in connection therewith.

Upon each end of the frame or body 9 I arrange transverse beams 16 and 17, the said beams 16 and 17 being supported above the said frame or body 9 by means of vertical uprights 18, and braced by means of bracing irons 20, which pass over said beams 16 and 17 and are secured to the longitudinal beams 14 and 15. On top of these transverse beams 16 and 17, I respectively arrange journaled boxes 21 and 22, in which the extremities of a spool 23 are journaled. This spool 23 consists of a hollow pipe, having separated disks 24 and 25 secured thereto. These disks 24 and 25 are respectively arranged adjacent the journaled boxes 21 and 22, whereby the canvas or tenting may be wound upon the hollow pipe 23 between the two disks 24 and 25. On the outer side of the disk 25, I secure a gear wheel 26 to the pipe 23. This gear wheel 26 meshes with an idle gear wheel 27, journaled as shown at 28, the said idle gear wheel 27 in turn meshing with a gear wheel 29 mounted upon a shaft 30. Also mounted upon this shaft 30, is a sprocket wheel 31, which is connected with the shaft 32 of an engine 33, by means of a sprocket chain 34, said sprocket chain 34

passing around said sprocket wheel 31 and around a similar sprocket wheel 35 mounted upon the engine shaft. I mount two fly wheels 36 and 37 upon the engine shaft 32; 5 however the construction of this engine is no part of my invention and any suitable kind of engine may be used. Now when the engine 33 is in operation the spool 23 will be caused to revolve through the medium of 10 the gear connection above described, whereby the canvas may be wound upon said spool. The sprocket wheel 31 is adapted to be made fast to the shaft 30 by means of a clutch, which clutch is operable by virtue of 15 a lever 38. Thus when it is desired to stop the spool 23 from revolving, the said clutch may be released, whereby the sprocket wheel 31 will be allowed to revolve upon the shaft 30 without causing the latter to 20 revolve. Thus the transmission of power will cease with the sprocket wheel 31, since the gear 29 is made fast to the shaft 30 and the latter must be revolved in order to transmit the power to the spool 23.

25 A guide rod 39 is connected with each end of the cross beams 16 and 17, the said guide rods being bent downwardly and connected with the frame or body 9. Cross bars 40 and 41 are arranged to slide upon these 30 guide rods 39. In other words the two guide rods at each extremity of the wagon are respectively connected by means of the cross bars 40 and 41. These two cross bars 40 and 41 rest upon longitudinally arranged beams 35 42 and 43 the said beams 42 and 43 are intermittently connected by means of iron members 44, in which hand screws 45 are swiveled. The beams 44 and 45 are also intermittently connected by means of cross 40 members 46, in which cross members the hand screws 45 are threaded. These hand screws 45 support the longitudinal beams 42 and 43, which in turn support the cross bars 40 and 41. The longitudinal beams 42 and 45 43 are provided on their upper surfaces with separated cross members 47, in the extremities of which rollers 48 are journaled. There is a series of these rollers 48 journaled in the extremities of these cross members 47 on each side of the longitudinal beams 42 and 43. For the convenience of 50 further description these series will be respectively numbered 49 and 50. These series of rollers 49 and 50 may be moved to and from the spool or pipe 23 by proper adjustment of the hand screws 45. In the course of moving these series of rollers to and from said spool or pipe 23, the cross bars 40 and 41 move upon the guide rods 39. 55 These cross bars 40 and 41 serve to hold the said rollers against lateral movement and to enable them to be properly adjusted in a vertical direction.

60 I journal upon the beam 14, longitudinally of the latter, rollers 51, said rollers being

70 journaled at their extremities in members 52' mounted upon the said beam 14 in separated condition from each other. In applying and removing the canvas or tenting from the spool, the same engages these rollers 51, thus preventing any frictional contact of the canvas with any stationary part of the wagon.

75 Now assuming that it is desired to wind the canvas upon the spool 23, the engine 33 will of course be started in operation which will result in transmitting power to the spool 23, causing the latter to revolve and wind the canvas therearound. As soon as 80 two or three layers of canvas have been wound upon the spool 23, the roll of canvas will then engage with the series of rollers 49 and 50, the latter serving to thoroughly pack and cause the canvas to be tightly wound around the spool 23. The provision of these 85 series of rollers 49 and 50 also prevent or obviate the canvas from sagging in the center of the spool, and said series of rollers causes the canvas to be uniformly packed throughout the entire length of the spool. 90 As the layers of canvas increase around the spool 23, these series of rollers 49 and 50 are correspondingly lowered by the proper adjustment of the hand screws 45, always, however, keeping said series of rollers 49 95 and 50 in close enough engagement with the roll of canvas upon the spool 23 to cause the said canvas to be thoroughly and uniformly packed throughout the length of the spool. These series of rollers 49 and 50 100 may of course be lowered by the proper adjustment of the hand screws 45 until the longitudinal beams 42 and 43 rest upon the bed of the wagon. After the canvas has been completely wound and packed upon the 105 spool in the manner above described, the hand screws 45 may be adjusted upwardly to raise these series of rollers 49 and 50 into tight engagement with the roll of canvas, where by the said roll will be firmly and compactly held in position by said rollers 49 and 50. 110

115 The transverse end beam 16 and 17, upon which the spool 23 is journaled, are braced by means of inclined members 52. These inclined members 52 which brace the transverse beams 16 on the front of the wagon, extend upwardly above the journal box 21 and are connected together at their upper extremities as shown at 53. A seat 54 is 120 connected to and partially supported by these members 52 on the front of the wagon, the said seat being shown connected with said members at a point 55. This seat 54 is also braced by means of rods or other suitable braces 56 which extend downwardly from the front of the seat and connect with the frame work of the wagon. A foot rest 57 is supported in front and slightly below the seat 54. This foot rest 57 is connected 125 130

with the front of the seat by means of a chain or other flexible device 58. Like all circus wagons or conveyances this foot rest or platform 57 may be raised to the vertical position to make the wagon in a compact form enabling the latter to be conveniently placed in a railway car for purposes of shipment. A hand wheel 59 is arranged in close proximity to the seat 54, said hand wheel 59 being secured to the upper extremity of a shaft 60. This shaft 60 is connected with the brakes 61 of the wagon, whereby by suitable or proper operation of the hand wheel 59 the brakes 61 may be either applied or released as desired.

In the use of my improved wagon for circus tents and canvas it will be understood that the wagon may be driven to the place where the canvas is to be loaded or unloaded, thus making it possible to attach the canvas to the spool 23 without dragging the canvas over the ground, in order to fold the same for the purpose of loading upon the wagon or conveyances heretofore used for the purpose of conveying the canvas from one place to another. In loading the canvas upon my improved wagon, all that is necessary is to first attach one end of the canvas to the roller 23 whereupon no further manual manipulation of the canvas will be required, but it will then be mechanically wound upon the spool 23.

The journal box 21, mounted on top of the transverse beam 16, is pivoted by means of a pivot pin 62, secured to said journal box and passing through the beam 17. The bottom of this journal box 21 is provided with a metal bearing plate 63, while the top of said beam 17 is provided with a coöperating metal bearing plate 64. By this arrangement the two journal boxes 21 and 22 are continuously kept in alinement with each other, whereby the journals of the spool 23 are prevented from binding when one wheel of the vehicle or wagon is in a depression of the ground or on a lower level than the rest of the wheels of the vehicle. That is if one of the wheels of the vehicle should be resting upon lower ground than the remainder of the wheels of the vehicle, the journal boxes 21 would turn upon a pivot to keep or maintain the two journaled boxes 21 and 22 in their alined position. In practice I have found that a construction of this character is very necessary in this wagon. In other words this wagon must be relatively long in order to properly accommodate the canvas used in circuses and for this reason when one wheel of the same is on a level lower than the other wheels, the two journal boxes will be moved out of alinement, unless, however, one of said journal boxes is pivoted as described in the foregoing.

65 While I have illustrated and described

herein a specific form of my invention it is understood that I am not limited thereto and that the same may be varied and modified without departing from the spirit of my invention or the scope of the appended 70 claims.

Having thus described my invention what I claim and desire to secure by Letters Patent is:—

1. Winding and reeling mechanism, comprising a spool, a support upon which said spool is journaled, rollers arranged longitudinally of said spool on opposite sides of the vertical plane of the axis of the latter, said rollers being arranged below the axis 80 of said spool, means for adjusting said rollers with respect to said spool, and another roller journaled below the axis of said first named rollers offset from the vertical plane of said first named rollers, substantially as 85 described.

2. Winding and reeling mechanism, comprising a portable support, a drum journaled upon said support, a roller mounted on said support longitudinally of said drum 90 offset from the vertical plane of the axis of the latter, and screws threaded in said support and operatively connected with said roller, whereby the latter may be adjusted with respect to said drum, and a second 95 roller journaled on said support and longitudinally arranged with respect to said first named roller, said last named roller being offset from the vertical plane of the axis of the said first named roller, substantially as 100 described.

3. Winding and reeling mechanism, comprising a drum, a support upon which said drum is journaled, guide rods mounted upon said support near the opposite extremities 105 of the latter, transverse members the opposite extremities of which are engaged with said guide rods, longitudinal members supported by said transverse members in separated relation, other transverse members 110 mounted upon said longitudinal members, rollers journaled longitudinally with said longitudinal members in said other transverse members, said rollers being respectively arranged adjacent either of said longitudinal members and in planes offset from the plane of the vertical axis of said drum, and means for vertically adjusting the plane 115 of said rollers with respect to said drum.

4. Winding and reeling mechanism, comprising a drum, a support upon which said drum is mounted, a roller carrying frame mounted upon said support below the axis of said drum, said frame comprising longitudinally arranged separated members extending parallel with said drum, guide members mounted upon opposite sides of said support near the opposite extremities of the latter, transverse members with which the extremities of said longitudinal members 125 130

are respectively connected, the extremities of said transverse members engaging with said guide members, rollers journaled upon said roller carrying frame on opposite sides of the vertical plane of the axis of said drum, and a plurality of adjusting screws upon which said roller carrying frame is mounted, said adjusting screws forming an adjustable connection for said frame between the latter and said support.

5. Winding and reeling mechanism, comprising a portable support, a drum journaled upon said support, a roller carrying frame vertically movable upon said support below the axis of said drum, guide members mounted upon said support near the opposite extremities of the latter, the opposite extremities of said roller carrying frame being engaged with said guide members, 15 rollers journaled upon said roller carrying frame, and a plurality of adjusting screws threaded in said support and engaging said roller carrying frame.

6. Winding and reeling mechanism of the class described, comprising a support, a drum journaled upon said support, an adjusting member carried by said support, a frame supported by said adjusting member below the axis of said drum, guide members mounted on said support near the opposite extremities of the latter, the opposite extremities of said frame engaging with said guide members, anti-friction members mounted upon said frame, and said adjusting member being operable to vary the distance of said frame from the axis of said drum, as the convolutions of the material increase around said drum for the purpose of tightening said material around said drum, substantially as described.

In testimony whereof I affix my signature in the presence of two witnesses.

WILLIAM H. CURTIS.
